CLAIM

The ornamental design for a paper product dispenser, as shown and described.

DESCRIPTION

FIG. 1 is a perspective view showing our new design for a paper product dispenser;

FIG. 2 is a front view of FIG. 1;

FIG. 3 is a back view of FIG. 1;

FIG. 4 is a left side view of FIG. 1;

FIG. 5 is a right side view of FIG. 1;

FIG. 6 is a top view of FIG. 1; and,

FIG. 7 is a bottom view of FIG. 1.

The claim is limited to the elements shown in solid lines. In the figures, the broken lines represent features that form no part of the claim.
